(57) **CLAIM**

The ornamental design for a patient table with control panel, as shown and described.

DESCRIPTION

FIG. 1 is a front elevational view of a patient table with control panel showing our new design;

FIG. 2 is a back elevational view thereof;

FIG. 3 is a top plan view thereof;

FIG. 4 is a bottom plan view thereof;

FIG. 5 is a right side elevational view thereof;

FIG. 6 is a left side elevational view thereof; and

FIG. 7 is a front, top, right perspective view thereof; and, FIG. 8 is a front elevational view of the control panel element of the patient table with control panel shown separately for clarity of illustration.

The broken lines are included for the purpose of illustrating portions of the patient table with control panel that form no part of the claimed design.

1 Claim, 8 Drawing Sheets
